A. WEBER

CRANK PIN TURNING TOOL

Filed Jan. 3, 1921

INVENTOR.
Alexander Weber,
BY *Frank Mac*
ATTORNEYS.

UNITED STATES PATENT OFFICE.

ALEXANDER WEBER, OF LOS ANGELES, CALIFORNIA.

CRANK-PIN-TURNING TOOL.

Application filed January 3, 1921. Serial No. 434,838.

To all whom it may concern:

Be it known that I, ALEXANDER WEBER, a citizen of the United States, and a resident of Los Angeles, in the county of Los Angeles, State of California, have invented new and useful Improvements in Crank-Pin-Turning Tools, of which the following is a specification.

My invention relates to tools of the character shown in my pending application for patent, filed February 10th, 1920, Serial No. 357,721, and an object is to provide a tool partaking of the characteristics of that shown in my previous application but having substantially different form.

A further object is to provide a tool of the character stated and adapted to be employed in a turning lathe or other suitable machine for initially finishing or refinishing the pins of crank shafts such as are used in internal combustion engines so that the peripheries of all of the pins will be positively parallel.

Another object is to provide suitable adjustments for accommodating the tool to different sizes of crank shafts.

Still another object is to provide a form of tool whereby it will be possible to so machine the pins of the crank shaft that a true circle will be generated and the work will be held in such a position relative to the tool that accuracy may be at all times preserved during the turning operation.

Referring to the drawing hereto annexed, in which a single embodiment of my invention is shown:

Fig. 1 is a side elevation of my improved tool, partly in section, showing the tool and the work in operative relation and in readiness for a finishing operation.

Fig. 2 is a partial plan view of the same.

Fig. 3 is an end elevation of the same.

Figs. 4 and 5, and 6, are respectively, transverse sections on lines 4—4, 5—5, and 6—6, of Fig. 1.

Fig. 7 is a view showing my tool in operative position in a lathe.

My improvements include an integral body B having a main tool supporting stem 1, a handle extension 2 disposed at an obtuse angle relative thereto and a work holding angular extension E, one of the legs 3 of which is at right angles to the handle extension 2 and the other leg 4 of which is at right angles to the leg 3. Bearing plates 5 and 6

are held on the inner faces of the legs 3 and 4, respectively, by means of screws 6', 6", etc.

The tool supporting portion 1 of the body B has a longitudinal channel 7 formed therein, which is closed at its outer end by means of a transverse portion 8, the said channel extending in the opposite direction throughout the length of the body portion 1 and upwardly into the leg 3 of the extension E, as shown in Fig. 1.

A tool carriage is provided for holding the tool in operative position relative to the work and is movably supported on the body by means of a block C which has an angularly cut recess 9 formed in the upper forward edge thereof to receive the tool T, said tool

having a width corresponding to the length of the crank pins to be finished thereby. A clamp C' is provided on the top of the block C for holding the tool firmly seated in the recess 9 and is adapted to be held detachably thereon by means of a cap screw 10, one portion 11 of said clamp engaging the top of the block C and the opposite portion 12 thereof engaging the top of the tool T, as shown in Fig. 1.

Block C has a depending extension 13 which extends into the channel 7 of the body portion 1 and serves to guide the tool carriage in its movement over the body, a plate 14 being attached thereto on the lower side of the portion 1 of the body by means of screws 15, 15 for retaining the carriage in operative position, as shown in Fig. 5.

A screw S is provided on the body B and has a bearing in the end 8 of said body, the forward end of said screw being threaded and extended through the depending extension 13 of the block C. An enlargement 16 is formed on said screw adjacent to the bearing 8 and a stationarily held collar 17 is held on the extended portion 18 of said screw on the opposite side of said bearing, as shown in Fig. 1.

A hand wheel H is attached to the end of the portion 18 of said screw by means of which the screw may be turned for advancing or retracting the tool carriage by means of the connections just described. Suitable graduation may be provided on the hand wheel 100 and on the stationary collar 17 for regulating and determining the extent of movement of the screw so as to properly set the tool T relative to the work W for making cuts of desired extent.

It will be noted that the elevation of the tool cutting edge *e* corresponds with that of the apex of the angle formed by the junction of the two bearing plates 5 and 6 on extension E, and said tool when adjusted to different positions for different sized crank pins will always be in a line paralleling the upper face of the body portion 1. It will also be noted, as indicated in Fig. 1 that lines drawn at right angles to the plane of the plate 5 of leg 3 of extension E and cutting the axis of the circles of crank pins of different diameters will, while necessarily intersecting the bisecting line of the angle between the legs 3 and 4 at the axes of said circles, also intersect the horizontal line of the tool cutting edge and the apex of the angle at points cutting the peripheries of said circles. Thus the cutting edge of the tool T will at all times be positioned slightly above the horizontal center lines of the circles and the work will be confined between the tool T and the bearing plates 5 and 6 in the finishing operation.

It is a common practice in the use of other tools for this purpose to so confine the work that the pressure of the tool thereagainst will be exerted substantially in the direction of the apex of the angle and the tool will be held practically on the bisecting line of the angle, but a true circle can not be generated in such a manner and it will be observed that in my tool the pressure is directed against the flat surfaces of the plates 5 and 6 rather than in the direction of the angle. This tends to preserve the proper form of the pins and to firmly hold the work in contact with two separate and right angularly disposed surfaces and constitutes two separate and spaced supports for the tool as against one in the other manner described.

In addition, however, to the above described means of supporting the work during the cutting operation, I provide an auxiliary supporting means consisting of a rest R having its lower end pivoted on a transverse pin 20 held in the portion 1 of the body and its upper end 21 engaging the periphery of the work at a point substantially on the bisecting line of the angle between the legs 3 and 4 of extension E. Portion 21 of member R is held upwardly in contact with the work by means of an adjusting screw A which is carried in a block 22 supported in the channel 7 of the body by means of pins 23, 23.

A plurality of bores 24, 24, etc., are provided in the body portion 1 for receiving the pivot pin 20 of the rests R, rests of different length being provided for crank pins of different size and the pin 20 is correspondingly moved from one to the other of the bores 24 for this purpose. Likewise, a plurality of the bores 25, 25, are also provided in the

body portion 1 for receiving the pins 23, 23 for supporting the adjusting screw block 22, and this block is also moved so as to engage the upper ends of the rests of different size. In Fig. 1 I have shown two rests of maximum and minimum length, respectively, in operative position.

As shown in Fig. 7, the work W is held in a lathe or other machine during the turning operation and the tool is fitted to the one of the pins of the crank shaft in the manner shown, by adjusting the tool carriage, rest and adjusting blocks and screws as described from one to another position. The lathe is then operated by power and the handle H of the tool will rest against the bed L of the lathe chuck in same manner as the connecting rod ends of an engine will move around the axis of the shaft bearings, and the tool T will engage and cut the periphery of the work W, throughout its entire length at one operation and to a uniform extent, until the proper diameter of the pin is attained.

Thereafter the tool may be changed to another of the pins and the operation repeated until all of the pins are turned to the proper size and are in true parallelism.

What I claim is:

1. A crank pin turning tool having right angularly disposed work engaging surfaces, and a tool movable relative thereto in a line at an angle of more than 45 degrees and cutting the apex of the angle between said surfaces, a body for supporting said tool having an extension disposed at an obtuse angle relative thereto, and means for confining the work between said surfaces and said tools.

2. A crank pin turning tool having a body, a work engaging surface obtusely disposed relative thereto, another surface at right angles to said obtuse surface, a tool held on said body and movable in a line paralleling said body and cutting the apex of the angle between said surfaces, for confining a pin therebetween, circles of pins of different size having their axis on a line bisecting the angle of said surfaces and said circles being tangential to said surfaces, and the diametrical lines of said circles when extended at right angles to said obtuse surface cutting the line of said tool on the peripheries of said circles at the intersections therewith of said diametrical lines.

3. A crank pin turning tool having a body, a right angular extension thereon having one of its legs disposed at an obtuse angle to said body, a tool held on and movable parallel with said body and in a line cutting the apex of said right angle, and a rest on said body for engagement with the work at a point substantially on a bisecting line of said angle.

4. A crank pin turning tool including a body having relatively horizontal and oblique stem and handle portions, a leg at right

- angles to said handle, a right angular extension on said leg, a tool held on and movable parallel with said body in a line cutting the apex of the angle between said leg and said extension, and adjustable means for confining the work between said tool and said legs. 5
5. A crank pin turning tool including a body, a pair of right angularly disposed work engaging surfaces disposed at angles relative to and integral with said body, a tool for engagement with said work, and an adjustable rest on said body for supporting work of different dimensions on a line bi-
- secting the angle of said work engaging surfaces. 15
6. A crank pin turning tool including a body arranged for selectively supporting work engaging means for confining the work during a finishing operation, and means adjustable from one position to another on said body for engagement with said work engaging means corresponding to the character of the work. 20

ALEXANDER WEBER.
